(57) **CLAIM**

We claim the ornamental design for a portable terminal, as shown and described.

DESCRIPTION

FIG. 1 is a perspective front view of a second embodiment of a portable terminal according to the present invention. FIG. 2 is a front elevation view of the portable terminal of FIG. 1.

FIG. 3 is a rear elevation view of the portable terminal of FIG. 1.

FIG. 4 is a right side elevation view of the portable terminal of FIG. 1.

FIG. 5 is a left side elevation view of the portable terminal of FIG. 1.

FIG. 6 is a top view of the portable terminal of FIG. 1; and, FIG. 7 is a bottom view of the portable terminal of FIG. 1. The broken lines shown are included for the purpose of illustrating portions of the portable terminal that form no part of the claimed design.
